UNITED STATES PATENT OFFICE.

CURT B. MUELLER, OF LAKEWOOD, OHIO.

DESIGN FOR AN AUTOMOBILE-BODY.

49,851.

Specification for Design.

Patented Nov. 7, 1916.

Application filed July 26, 1915. Serial No. 42,095. Term of patent 7 years.

To all whom it may concern:

Be it known that I, CURT B. MUELLER, a citizen of the United States, residing at Lakewood, in the county of Cuyahoga and State of Ohio, have invented a new, original, and ornamental Design for Automobile-Bodies, of which the following is a specification, reference being had to the accompanying drawing, forming part thereof, in which—side elevation showing my new design, while Fig. 3 is a rear perspective.

I claim:

The ornamental design for an automobile body as shown.

CURT B. MUELLER.

Witnesses:

NINA DE VALL,
CLARA B. CUMMINS.
